James H. Fairbanks of Philadelphia, Pennsylvania
Savers Patent.

The block will referred to in these Letters Patent and making part of the same containing a description of the mode of the said James H. Fairbanks himself of his improvement in constructing Rail Road Cars.

Be it known that witness James H. Fairbanks of the City of Philadelphia in the State of Pennsylvania invents a new and useful improvement in Cars for running on Rail Roads, and that the following is a full and exact description of the construction and operation of the said Car combining advantages improved by me. The frame or side is generally called the wood or part of this car is similar to those in common use with the exception of a piece of timber or other substance of sufficient strength extending longitudinally of the car at equal distances from each side and of a equal height from the rails to meet or attack the upper vertical rollers, hereafter mentioned to provide the following described base, plates and bearing, for the journals of the axles to run in to rest, plates of iron or other strong substance of sufficient width, length, and thickness, with circular flanges on the one side or outer edge thereof, and may downwardly a sufficient distance to contain the upper vertical vertical rollers and necessary braces or bearings, in which the journals of the axles run. The radii of the inner and concave side of the circular flanges, being half the length of the arch or arch on which the wheels are fastened. These plates shall be fasten to the frame of the car in their proper places to suit their corresponding journals of the two axles by iron bolts of sufficient strength to provide for each bearing two or more vertical rollers of sufficient diameter, length and strength which stand in a slanting form, each end forming part of a cone, the vertex of which is the middle distance between the ends of the axles, and this plate is made horizontal as the cone, will consist of two vertical vertical rollers, two or more for each of the vertical rollers, confined within the concave part of the iron frame, and of the same diameter as the largest diameter of the vertical vertical rollers, the journals of all the rollers being covered by a round iron plate, this upper iron plate being so made to prevent the upper vertical rollers as to admit them from

to vibrate freely with the rollers, without friction by coming in contact with the underside of the uppermost horizontal plate or inside of the outer, smaller flange, through, against which plate and flange the periphery of the rollers bears, these plates forming a horizontal circular groove in which, for each box, in which groove I place a movable box resting against the periphery of the rollers in which box the journal of the axle turns, at or near the ends of the aforesaid plates. Of iron vertical flanges to prevent the said boxes from vibrating further than necessary, and to enable me to make the whole box rolling and journals, and thereby keep out the dust and to contain therein a sufficient quantity of oil which I supply through an aperture in the upper plate, of two wide horizontal circular plates or rings of less diameter than the distance between the wheels on their corresponding axles. The centers of these two circles or rings are the middle distance from the ends of the axle or shafts. These circles or rings to their proper place by bars connecting them with their respective axles and the axles passing through and resting in these bars. To the first mentioned piece of timber or other material of sufficient strength I attach two vertical friction rollers for each of said circles to rest against, and roll when acted on by the force of the wheels, and vibrating of the axles. The middle distance between each end of the axle is common to the centre of the conical rollers, and the cones formed by them at each end of the axle and to the centre of the two horizontal circles in which the vertical rollers are placed. The operation of this car is as follows. The wheel, being connected with their axles, opposite will always adjust the axles at right angles with the railway crooked or straight, which at the same time the car passes over the same. They have no tendency to leave the track on a curve, and prevent the flanges of the wheels from striking against the inside of the rails, and the whole with the above arrangement and construction of boxes and horizontal circles, conical and vertical rollers operate freely with an immense saving of friction on curves. In after case of locomotive engine already made, without effecting the engine. Let the axles and iron plates remain as they are and take one wheel. I therefore claim the exclusive right to the invention of the construction of the above boxes, rollers and circular plates or rings as applied by me to cars travelling on the roads and all other parts of the above mentioned
